(57) **CLAIM**

The ornamental design for an air fryer oven, as shown and described.

DESCRIPTION

FIG. 1 is a left side view of an air fryer oven in accordance with my design;

FIG. 2 is a back view thereof;

FIG. 3 is a top view thereof;

FIG. 4 is a front view thereof;

FIG. 5 is a right side view thereof;

FIG. 6 is a bottom view thereof;

FIG. 7 is a front left perspective view thereof; and,

FIG. 8 is front right perspective view thereof.

The broken lines show portions of the air fryer oven that form no part of the claimed design.
